UNITED STATES PATENT OFFICE

ALFRED THOMAS SCOREY, OF LONDON, ENGLAND.

HAND-PROPELLED FOLDING CARRIAGE OR CHAIR.

1,300,033.

Specification of Letters Patent.

Patented Apr. 8, 1919.

Application filed August 2, 1916. Serial No. 112,881.

To all whom it may concern:

Be it known that I, ALFRED THOMAS SCOREY, a subject of the King of Great Britain and Ireland, residing at 75 Great Titchfield street, London, W., England, have invented new and useful Improvements in Hand-Propelled Folding Carriages or Chairs, of which the following is a specification.

This invention relates to cross-frame folding carriages or wheeling chairs for children in which a long frame forming the handle frame and fitted with wheels at its lower end is pivotally connected to a short frame also fitted with wheels at its lower end and having arm rests pivotally connected with its upper end and extending rearwardly to the handle frame, said arm rests limiting the opening movement of the frames.

One object of my invention is to provide a folding carriage of this type which, while being extremely comfortable in use shall collapse sidewise as well as from front to back and shall occupy when folded or collapsed much less space as compared with known folding carriages and shall consequently be much more convenient to store, handle or carry.

Another object of the invention is to provide a folding carriage of the type referred to with shock absorbing means with a view to eliminating the jolting inseparable from the rigid type of carriage which is known to be especially harmful to young children.

My invention consists in so arranging the side members of the main frame with the wheels thereof and the arm rests that these parts can be turned about their pivots into exact parallelism when the carriage is being folded, also in connecting the side members of each main frame by pivoted stays having a sliding connection with their respective frame members at one end whereby the said frames are made collapsible so that the opposite parallel sides can be brought close together, the stays lying along opposite sides of the juxtaposed side members of the main frames. In this position all the frame members of the carriage lie close together in a compact group which can be easily carried in the hand, the wheels also being close together and co-axial.

To permit of the folding and collapsing of the frames as described the seat which is made of webbing or similar material is slung

on flexible straps or the like attached to the sides of the frames.

My invention also consists in providing a sliding connection between the rear ends of the arm rests and the main frames and interposing shock absorbing springs which impart resiliency to the frame and absorb most of the shocks which would otherwise be transmitted to the seat.

The invention is hereinafter described with reference to the accompanying three sheets of illustrative drawings in which the same letters of reference are employed to denote the same parts in different views.

In the drawings:

Figure 1 is a side elevation of a child's folding carriage constructed according to this invention, and shown opened for use.

Figs. 2 and 3 are front and side elevations respectively showing the carriage partly folded.

Fig. 4 is a rear elevation showing the carriage completely folded or collapsed.

Fig. 5 is a detail view partly in section on a larger scale illustrating the shock absorbing connection between the rear ends of the arm rests and the handle frame.

Fig. 6 is a detail view illustrating the connection between one of the crossed stays and the side member of the cross frames, and

Fig. 7 is a detail section taken at right angles to Fig. 6.

As shown the handle frame consists of two straight side members *a* with wheels *b* mounted directly under the lower ends thereof in forks or brackets *c* conveniently formed of straight flat plates while the upper ends of the frames form handles. The side members *a* are connected by a pair of stays *d* disposed cross wise, pivoted together at the middle point *e* where they cross and also pivoted to the frame members *a*. At their lower ends the stays *d* have a simple pivotal connection *d'* the outer stay being suitably spaced from the frame member at the pivot by a washer to insure it passing freely over the inner stay when folding.

At their upper ends, the stays are provided with studs or sliders *f* arranged to work in slots *g* in the frame members, Figs. 6 and 7, in which they are held by slotted guide plates *h* fixed over the slots in the frame members, the said sliders being held

at one end of their respective slots when the frame is extended by a spring catch *i* which engages the slider but is capable of being easily released by pressing on a small projecting finger piece *i'*.

The shorter main frame which is pivoted within the handle frame below the stays thereof is formed of straight side members *a'* provided with wheels *b'* and collapsible stays *d'* in a similar manner to the handle frame *a*. Arm rests *j* are pivoted to the upper ends of the short frame and are slotted longitudinally at *l* to receive bolts or studs *k* which are fixed in the handle frame 10 as clearly shown in Fig. 5. Between the bolts *k* and the rear ends of the slots in the arm rests helical springs *m* are interposed which serve to absorb shock as described. In order to strengthen the arm rests the 15 ends are preferably capped with metal strips *n*.

The seat of webbing or the like *o* is slung between two round straps *o'* *o''* one of which is stretched across the handle frame near the 20 handles, while the other is attached to the short frame across the front ends.

A strap or sling, not shown, serving as a foot rest, may also be suspended on the short frame.

30 In folding or collapsing the carriage the cross frames are first folded parallel as shown in Fig. 2, the arm rests *j* sliding over their bolts *k* and taking up positions in line with the side members *a'* of the short frame. 35 The catches *i* holding the crossed stays of the side members of the cross frames are then released and allow the frames to be further collapsed, as described, to the position shown in Fig. 4. Handles may be 40 provided on the handle frame for assisting in opening the carriage and for carrying it when folded.

What I claim and desire to secure by Letters Patent is:—

45 1. A folding carriage or wheeling chair comprising pivotally connected main frames, each consisting of a pair of parallel spaced, side members, arm rests limiting the opening movement of the frames about their

pivots and arranged to move into line with the side members of one of the frames when the carriage or chair is being folded, and pivoted cross stays connecting the side members of the main frames said stays having a sliding connection with the frame members at one end, the whole arrangement being such that the main frame members are capable of being folded or collapsed into exact parallelism and the opposite parallel sides of the main frames brought close together substantially as described.

2. A folding carriage or chair comprising a pair of laterally collapsible main frames, a pair of arm rests, a pair of longitudinally collapsible seat-supporting elements, and 65 a collapsible seat, said frames being pivotally connected together so as to fold substantially into parallelism, said arm-rests being movably connected to said frames in a relation to be foldable substantially into 70 parallelism with the frames when the latter are folded, said longitudinally collapsible seat-supporting elements being connected to opposite sides of the respective frames, said collapsible seat being suspended 75 between and supported by said longitudinally collapsible seat-supporting elements.

3. A folding carriage or chair comprising a relatively long laterally collapsible frame, a relatively short laterally collapsible frame 80 pivotally connected to the long frame and crossing the latter, a pair of arm rests each pivotally connected to the short frame and slidably connected to the long frame in a relation to be substantially horizontal when 85 in the useful position, a longitudinally collapsible seat-supporting element connected to the long frame above said useful position of the arm rests, a longitudinally collapsible seat-supporting element connected 90 to the short frame below the pivotal connections of said arm rests, and a collapsible seat-supporting elements and constituting a seat and a back rest.

In testimony whereof I affix my signature.

ALFRED THOMAS SCOREY.
